(57) **CLAIM**

The ornamental design for a jack toy, as shown and
described.

DESCRIPTION

FIG. 1 is a perspective view of a jack toy showing my new
design;

FIG. 2 is a partially rotated elevational view of the left front
side of FIG. 1, shown on a reduced scale and without
perspective distortion;

FIG. 3 is an elevational view of the opposite side of FIG. 2;
FIG. 4 is an elevational view of the bottom of FIG. 2 rotated
clockwise 90°;

FIG. 5 is an elevational view of the opposite side of FIG. 4
and of the upper end of FIG. 2 rotated counterclockwise 90°;
FIG. 6 is an elevational view of the right side of FIG. 2,
rotated clockwise 90°; and,

FIG. 7 is an elevational view of the opposite side of FIG. 6
rotated clockwise 90°; and of the left side of FIG. 2.
